UNITED STATES PATENT OFFICE.

JOHN E. HOFFMAN, OF CASPER, WYOMING.

WRECKING TOOL.

Application filed October 20, 1923. Serial No. 669,767.

To all whom it may concern:

Be it known that I, JOHN E. HOFFMAN, a citizen of the United States, residing at Casper, in the county of Natrona and State 5 of Wyoming, have invented certain new and useful Improvements in Wrecking Tools; and I do hereby declare the following to be a full, clear, and exact description of the invention, such as will enable others skilled 10 in the art to which it appertains to make and use the same.

The object of the present invention is the provision of a tool whereby scaffolding and frame structures generally may be taken 15 apart without injury to boards and like material, so that the same may be advantageously reused.

In accordance with the present invention, the tool comprises a pry, such as a lever, an 20 anchoring member having the pry pivoted thereto and adapted to engage a steady member such as a post, beam or stud, and a shoe for distributing the pressure of the pry upon the board or like part to be detached.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the spirit of the invention.

Referring to the accompanying drawings forming a part of the application:

Figure 1 is a perspective view of one form of the invention showing the same as it appears when in operation,

Figure 2 is a detail sectional view of the parts illustrated in Figure 1,

Figure 3 is a front view of the shoe, the anchoring member and the sliding connection to which the shoe is pivoted,

Figure 4 is a view similar to Figure 1 of a modification,

Figure 5 is a view similar to Figure 2 of the modified form, and

Figure 6 is a view similar to Figure 3 of the corresponding parts of the modification.

Corresponding and like parts are referred to in the following description and designated in the several views of the drawings by like reference characters.

The numeral 1 designates a post, stud or

the like to which a board 2 is attached, these parts being shown to demonstrate the application of the invention.

The numeral 3 designates a pry which 60 may consist of a bar of any preferred form having a cam 4 at its active end, said cam preferably forming a part of the pry. An opening 5 separates an intermediate portion of the cam 4 from the body 3 of the pry 65 and besides lightening the structure provides for the reception of a pin 6 or like connection whereby the shoe 7 is connected to the pry to prevent displacement of the parts.

The anchoring member 8 is provided at its forward end with a short crossbar 9, either end of which is adapted to engage a post 1 or like part according to the arrangement of the tool upon one side or the other 75 of the part 1. The member 8 is elongated and receives a slide 10 to which the shoe 7 is pivotally connected at 11. A helical spring 12 connects the slide 10 with the member 8 and normally holds the slide with- 80 in the member. The member 8 is hollow and encloses the slide 10 and spring 12 which are retained in place within the opening 13 formed in the said member. The pry 3 is pivoted to the member 8 adjacent the cross- 85 head 9, as indicated at 14.

The shoe 7 consists of an elongated plate of a size to effectively distribute the pressure of the pry upon the element 2 and its upper end is reduced and extends through 90 the bottom of the member 8 and is pivoted to the slide 10, as indicated at 11. Spaced ears 15 projecting from the plate 7 embrace opposite sides of the cam 4 and their outer ends are connected by means of the pin 6. 95 In the modification shown in Figure 4 and the detail views thereof, the pry 3 is substantially the same as herein before described and is pivoted at 14 to the shoe 8^a which is bifurcated at its rear end, the bifurcations 8^b being curved and embracing opposite sides of the pry 3 whereby to assist materially in maintaining the parts in alignment. The forward end of the anchoring member 8^a is provided with a cross-head 9. The shoe 7 is substantially the same in construction and operation as the corresponding part herein before described and is connected at its upper end to the anchoring member 8^a by means of a helical spring 16. The spring 16 performs the same function as the slide 10 and spring 12 of

the form shown in Figure 1 and the detail view thereof and constitutes a yieldable connection between the shoe and anchoring member, whereby said parts may move and adapt themselves to the changed relation brought about incident to the operation of the pry 3.

In the operation of the tool, the same is disposed so that an end of the crosshead 9 engages the part 1 and the shoe 7 the part 2 and upon operating the pry 3, the cam 4 thereof exerts a pressure on the shoe 7 and by reason of the pivotal connection of the pry with the anchoring member, the latter and the shoe are moved in opposite directions and as a result the board 2 is detached from the post 1 or like part and by reason of the shoe distributing the pressure, the board is detached without appreciable injury thereto which would preclude its further effective use.

What is claimed is:

1. A wrecking tool of the character specified, comprising an anchoring member, a pry pivoted at one end to the anchoring member and having a cam at one side spaced therefrom intermediate its ends, a shoe having spaced ears embracing opposite sides of said cam, a pin connecting the free ends of said ears and adapted to engage the inner edge of the cam, and a yieldable connection between the shoe and anchoring member, said anchoring member having ears extended to provide portions embracing opposite sides of the pry adjacent the pivotal connection of the pry therewith.
2. A wrecking tool of the character speci-

fied, comprising an anchoring member, a pry pivoted at one end to the anchoring member and having a cam at one side spaced therefrom intermediate its ends, a shoe having spaced ears embracing opposite sides of said cam, a pin connecting the free ends of said ears and adapted to engage the inner edge of the cam, and a yieldable connection between the shoe and anchoring member, said yieldable connection comprising a slide mounted upon the anchoring member and having the shoe pivoted thereto, and a spring between the slide and anchoring member.

3. A wrecking tool of the character specified, comprising an anchoring member, a pry pivoted at one end to the anchoring member and having a cam at one side spaced therefrom intermediate its ends, a shoe having spaced ears embracing opposite sides of said cam, a pin connecting the free ends of said ears and adapted to engage the inner edge of the cam, and a yieldable connection between the shoe and anchoring member, said yieldable connection comprising a slide and spring housed within the anchoring member, said slide having the shoe pivoted thereto and the spring connecting the slide with the anchoring member.

In testimony whereof I affix my signature in presence of two witnesses.

JOHN E. HOFFMAN.

Witnesses:

CLARA ADKINS,
LOIS LONGSHORE.
